DEVICE FOR HOLDING GARBAGE CANS

Herbert B. Fallis, Wichita, Kans.

Application October 6, 1941, Serial No. 413,883

1 Claim. (Cl. 248—310)

This invention relates to an improved device for holding a garbage can so as to prevent accidental upsetting thereof, as by means of dogs and cats attempting to gain access to the contents of the garbage can.

The present invention also relates to an improved device, operable by the foot, for opening the lid of a garbage can, whenever it is desired to deposit garbage in the can or to empty the garbage therefrom.

An object of the present invention is to provide a garbage can holder of the above kind which is extremely simple and durable in construction and efficient in use.

A further object of the present invention is to provide a foot operated device for opening the lid of a garbage can, which device is readily adjustable for use with garbage cans of different sizes, both in cross-section and in vertical height. Other objects and features of the invention will become apparent from the following description when considered in connection with the accompanying drawings, in which:

Figure 1 is a side elevational view, partly broken away and in section, showing a garbage can operatively associated with a holder and lid opening device constructed in accordance with the present invention;

Figure 2 is a top plan view thereof;

Figure 3 is a rear elevational view of the device, partly in section;

Figure 4 is a horizontal section taken on line 4—4 of Figure 1 and partly broken away;

Figure 5 is a fragmentary elevation, partly broken away and in section, showing the means for connecting the horizontally swinging arm of the lid opening device with the handle of the lid;

Figure 6 is a sectional perspective view of the spirally grooved tubular member forming part of the means for causing the horizontal swinging arm to be actuated when elevated; and

Figure 7 is a transverse cross section taken on the line 7—7 of Figure 1.

Referring in detail to the drawings, the present invention includes a can holder or stand consisting of an upright 5 preferably consisting of a sheet metal plate whose major lower portion is reinforced by means of side or longitudinal flanges 6. Rigid with the lower end of upright 5 and extending in diverging relation therefrom are horizontal channel members 7 whose intermediate or base portions are provided with central longitudinal elongated slots 8. Angular members as associated with the channel mem-

bers 7, the lower horizontal arm 9 of each angular member being slidably fitted in one of the channel members 7, and the other vertical outer arm 10 of each angular member projecting upwardly as shown. A wing bolt 11 passes upwardly through the slot 8 of each channel member 7 and is threaded into the associated arm 9. By tightening the thumb bolts 11, the angular members 9, 10 may be secured in adjusted position relative to the channel members 7, and it will be seen that the body 11' of a garbage can is adapted to be disposed upon the horizontal arms 9 and contacted at spaced points by the arms 10 and upright 5 so that the can will be effectively held in a desired position and is prevented from accidentally upsetting. By loosening thumb bolts 11, the arms 10 may be adjusted into snug contact with the can body while it also contacts the upright 5, said thumb bolts being subsequently tightened to secure the adjustment. The holder may be suitably anchored to the ground, as by means of a threaded stud 12 projecting downwardly from the lower end of upright 5 and threaded into the upper end of a pipe or other threaded member 13 embedded and anchored in the ground. The outer or spaced ends of the channel members 7 may be rigidly connected by means of a suitable connecting bar 14 so that any spreading strains on said channel members 7 will be effectively resisted and so that said channel members will be effectively braced in their proper diverging relation.

The present invention also includes simple and efficient means for raising and then swinging the lid 15 of the can 11' laterally to an out of the way position as shown by dotted lines in Figure 1 so that access may be had to the can 11' for placing garbage therein or for permitting removal of the can 11' to empty the contents thereof. This means includes a vertical shaft having a hollow upper section 16 journaled in a bearing 17 on the outer side of the upper end of upright 5, and a lower section 18 journaled in a bearing 19 on the outer side of the upright 5 near its lower end. The shaft sections 16 and 18 are slidably telescoped so that the length thereof may be adjusted, and the lower end portion of section 16, is split as at 20 and encircled by clamping band 21. By loosening the clamping band 21, the length of the shaft may be properly adjusted, and by tightening the band this adjustment may be secured in a generally well known way. Rigid with the upper end of shaft 16, 18 is a horizontal arm including an inner hollow section 22 rigid with the shaft section 16 and an outer arm sec-

tion 23 slidably telescoped into the section 22. The outer end of section 22 is split as at 24 and encircled by a clamping band 25 which may be loosened to permit adjusting the length of the arm 22, 23 and then tightened to secure the adjustment. By providing the adjustable shaft and arm, the device may be adapted for use with cans of different sizes, both in horizontal cross-section and vertical height. The outer end of arm 22, 23 is suitably fastened to the handle 26 of the lid 15, which handle is in the usual form of a U-shaped hand grip of curved transverse form as shown more clearly in Figure 5. This fastening means preferably consists of a clamping plate 27 and a U-bolt 28 having its threaded ends passing upwardly through end apertures in the plate 27, nuts 29 being threaded on the ends of U-bolt 28 above the plate 27. The clamping plate 27 is attached to arm section 23 by means of a depending threaded stud 30 rigid with the arm section 23 and threaded centrally into the plate 27. In practice, the intermediate portion of plate 27 is thickened and provided with a convex under-side adapted to fit the concaved upper surface of handle 26, the intermediate portion of U-bolt 28 being arched to fit the under-side of said handle. By tightening the bolts 29, the intermediate portion of handle 26 may be firmly clamped between the plate 27 and the U-bolt 28.

As shown more clearly in Figure 6, the lower bearing 19 has diametrically opposed vertical grooves 31 in the lower portion thereof which are normally engaged by the ends of a cross pin 32 extending through the shaft section 18. Extending upwardly from the upper ends of vertical straight grooves 31 are spiral grooves 33 into which the ends of pin 32 will pass from the grooves 31. By this means, the shaft 16, 18 may be elevated for the length of the grooves 31 without being rotated so as to lift the lid 15 completely off of the can body 11', after which the shaft 16, 18, upon being further elevated, will be caused to turn and thereby swing the arm 22, 23 and the lid 15 laterally for a sufficient distance to position the lid 15 entirely out of the way as indicated by dotted lines in Figure 1. This rotation of the shaft is effected by the engagement of the ends of pin 32 in the spiral grooves 33, as will be apparent. In order to manually operate shaft 16, 18 for causing the above operation, I provide a pedal 34 mounted upon a horizontal pivot 35 on the lower portion of upright 5 so that an arm of said pedal engages the lower end of shaft section 18. By applying foot pressure to the other end of pedal 34 so as to swing the latter in the direction of the arrows

shown in Figure 3, the shaft will be elevated in the desired manner. It is further noted that the pedal 34 is movable laterally on the pivot pin 35 so that by pressing the pedal 34 laterally toward the upright 5 after the shaft 16, 18 has been completely elevated, the depressed arm of pedal 34 may be engaged under a lug 36 rigid with the upright 5 for holding the lid in its out of the way position shown by dotted lines in Figure 1. 5 Conversely, the pedal 34 may be slid away from the upright 5 on the pivot 35 to disengage it from the lug 36, whereupon the parts may be returned to normal position by simply swinging the arm 22, 23 back to the full line position of 10 Figure 1. When this takes place, the lid 15 reaches a position over the top of can 11' and then lowers vertically onto the upper end of the latter. At the same time, pedal 34 returns to its 15 position of Figure 3, excessive return swinging 20 movement of said pedal being prevented by means of a suitable stop pin 37 carried by the upright 5 beneath the inner arm of said pedal.

From the foregoing description, it is believed that the construction and operation, as well as 25 the advantages of the present invention, will be readily understood and appreciated by those skilled in the art. The construction is extremely simple and durable, and affords an efficient and 30 comparatively inexpensive device for effectively carrying out the stated objects of the invention. Minor changes may be made in the details of 35 construction illustrated and described, without departing from the spirit and scope of the invention as claimed.

35 What I claim as new is:

In a garbage can support, a channeled upright having the lower end thereof reduced to cylindrical shape and screw threaded for threading into a ground anchor, a horizontally arranged V-shaped member having the apex thereof formed on the upright adjacent to and above the reduced lower end of said upright, a brace connecting the ends of the member, said member having channels in the diverging portions thereof and provided with slots located in the channels, L-shaped members including vertical and horizontal portions and having the horizontal portion 40 slideable in the channels for the adjustment of the vertical portions toward and from the upright to receive and grip cans of different sizes, and thumb screws extending through the slots and 45 threaded into the L-shaped members for releasably securing said L-shaped members in adjusted positions.
